US0D1050462S

(12) **United States Design Patent** (10) **Patent No.:** **US D1,050,462 S**
(45) **Date of Patent:** **** Nov. 5, 2024**

(54) **HEATING CUSHION**

(71) Applicant: **Guangzhou Acomir Electronic Commerce Co., LTD.**, Guangzhou (CN)

(72) Inventor: **Peng Du**, Guangzhou (CN)

(73) Assignee: **Guangzhou Acomir Electronic Commerce Co., LTD.**, Guangzhou (CN)

(**) Term: **15 Years**

(21) Appl. No.: **29/860,331**

(22) Filed: **Nov. 17, 2022**

(51) **LOC (14) Cl.** **24-01**

(52) **U.S. Cl.**

USPC **D24/206**; D7/367

(58) **Field of Classification Search**

CLAIM

The ornamental design for a heating cushion as shown and described.

DESCRIPTION

FIG. 1 is a front, right and top perspective view of a heating cushion, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The broken lines depict portions of the heating cushion that form no part of the claimed design.

1 Claim, 8 Drawing Sheets
